DOOR LATCH

Franz Netschert, Glendale, Calif., assignor to
 Technical Glass Company, Los Angeles, Calif.,
 a corporation of California

Application December 21, 1946, Serial No. 717,644

2 Claims. (Cl. 292—359)

1

This invention relates to latches of the kind fitted with a small operable part on the handle on the inside of the door to enable it to be locked without the use of a key.

It is an object of the invention to provide a latch of the kind described, having mechanism arranged so that the latch may be retracted by turning the handle on either side of a door in either direction, but by operating a small lever mounted in one escutcheon plate to be able to lock the latch.

It is a further object of the invention to provide latch mechanism operable from either side of a door and fitted with a locking mechanism incorporated in the escutcheon plate on one side of the door, but arranged so that by proper manipulation of the handle on the opposite side of the door it may be unlatched.

It is a still further object of the invention to arrange the locking mechanism of a latch of the kind described so that the operation of the locking mechanism will be positive, eliminating backlash which may be detrimental to the functioning of the mechanism.

Still further objects and features of the invention will hereinafter appear from the following description taken in conjunction with the accompanying illustrative drawings in which is shown an embodiment of the invention at present deemed preferable by me.

In the drawings:

Fig. 1 is a vertical section taken through the spindle, escutcheon plates, and locking mechanism mounted therein, of my invention;

Fig. 2 is a section on the line 2—2 of Fig. 1;

Fig. 3 is an exploded view showing the component parts of the latch locking mechanism in their order of assembly;

Fig. 4 is a detailed view in side elevation of a locking piece; and

Fig. 5 is a cross section on the line 5—5 of Fig. 4;

Fig. 6 is a longitudinal section through a modified form of latch member; and

Fig. 7 is a detail drawn to a larger scale of a cam member in the latch shown in Fig. 6.

In the drawings, the numeral 10 indicates the handle on the outside of a door, which is secured in a socket member threadedly mounted on a spindle 14, which is of rectangular cross section. The spindle passes through a latch member generally indicated at 16, and is resiliently connected to an extension spindle indicated generally at 18. An inner handle or knob 20 is threadedly secured to the extension spindle and

2

locking mechanism generally indicated at 22 is mounted in the escutcheon plate 24 on the inner side of the door.

The latch unit 16 may be of any type which enables the latch to be retracted by either door knob being turned in either direction. The latch mechanism shown, by way of example, in Fig. 2, comprises a cylindrical housing 28 formed with removable cover to enable the mechanism to be placed in the housing, in Fig. 2, the housing cover is shown with the cover removed. The mechanism comprises a latch 30 formed as an extension of a slide 32 having a downwardly turned flange 34 and an upwardly turned flange 36, the latter limiting forward movement of the latch through an opening in the front end of the housing. A flat bar 38 is arranged to project across the interior of the housing, and a helical spring 40 is compressed between the flat bar and the upturned flange 36 to normally hold the latch in projected position. The slide may be retracted by a second slide 42 having an upwardly extending flange 44, and a second helical spring 46 arranged between the upwardly extending flange and the flat bar 38. A laterally projecting finger 48 extends from the slide 42 into engagement with the downwardly turned flange 34 of slide 32. The rearward end of slide 42 is provided with an opening 50 embracing a cam member 52 through which the spindle 14 extends. The rearward end of slide 42 is provided with an upwardly extending flange 54 terminating in forwardly directed rounded surfaces engaged by flat surfaces of the semi-circular cam 56 carried by the cam member 52. On rotating either door knob, the semi-circular cam will engage and force backwardly the retracting slide 42, which will in turn retract the latch slide 32.

Locking of the latch 30 is effected by mechanism acting to prevent the rotation of the spindle 14 and extension spindle 18. The locking mechanism is shown in detail in Fig. 3 and comprises a stamped shell 58 fitting within the escutcheon plate 24. The stamped shell comprises recesses 60 and 62 which receive a locking member, or lever, 64, the recess 62 also receiving a small leaf spring 66 serving to hold the locking member 64 in either open or locked position. The locking member extends through cutout portions 62a of the stamped shell and 24a of the escutcheon plate 24.

A locking plate 68 fits into a central depression 70 in the stamped shell and is furnished with a parallel sided opening 72 fitting on the extension spindle 18. The locking plate is provided with

four recesses 14, arranged at right angles to one another, the side walls of the recesses being tapered slightly inwardly toward one another. A locking piece 76 is positioned against the locking plate 68, the shape of this locking piece being shown in detail in Figs. 4 and 5, from which it will be observed that the plate is furnished with a projecting arm 78 which is received in the recess 80 stamped in the shell 58, and with a downwardly turned finger 82 received in recess 83 of the shell 58. The end of finger 82 is adapted to enter and wedge in any one of the recesses 14 when operated by the locking member 64. Both the locking piece 76 and locking member 64 are provided with a central recess clearing the extension spindle 18, but the recess in the locking member 64 is sufficiently large to permit of a rocking movement of the member 64 about its lower end.

The operation of the locking mechanism is as follows: If the member 64 is placed by pushing knob 84 in position at one end of its slot 24a, such that finger 82 is moved clear of notches 14, spindle 14 may be freely turned. If member 64 is rocked to the opposite end of its travel while knob 20 is rotated slightly, finger 82 will snap into one of notches 14 and by reason of the tapered walls thereof will firmly hold locking plate 68 against rotation and thus will hold extension spindle 18 against rotation. The spindle, while being resiliently connected to spindle 14 is arranged in normal position, to turn with spindle 14 by virtue of the construction now to be described.

Extension spindle 18 is of somewhat greater cross section than spindle 14 and is resiliently held for turning therewith by means of a rectangular recess in the enlarged end 86 of spindle 18 which recess fits snugly on the rectangular spindle 14.

The recessed head of the enlarged end 86 is normally held in engagement with spindle 14 by a spring 88 engaging between the head 90 of a machine screw 96 passed through an axial smooth walled bore 92 in the end of stem 14. The machine screw may be retained in adjusted position in the bore in spindle 14 by dimpling the end of spindle 14 with a center punch as indicated at 94 to jam the machine screw in the threaded bore. The construction described, enables the spindle to be easily and quickly assembled and the load on the spring to be adjusted so that a pull of desired strength is required to bring the end of spindle 14 free of spindle 18, and provides the feature that should the locked door require to be opened from the outside, for instance, as may happen in the case of a young child who unknowingly locks himself into the room while playing with the door handle, or an invalid subject to fainting spells who has locked the door but is unable to unlock it because of such a spell, a nurse or other party can open the door from the outside by pulling strongly on the outside door knob and then turning the knob in either direction.

In Fig. 6, I show a form of latch in which a single spring 98 is provided normally holding the latch 100 in projected position, but permitting the latch to be pushed into the door by the door jamb when closing the door without turning the handle.

The latch 100 is assembled in a case not visible in the figure to which an abutment for the spring is secured. The construction of the latch per se is fully described in my co-pending application,

Serial No. 672,148, filed on May 5, 1946, to which reference may be had, but the present invention is not concerned with the particular type of latch provided, but with locking means therefor, of the kind described, and the adaptability of the parts to latches of various types, of which two are given, by way of example.

The latch shown in Fig. 6 is withdrawn by means of a double cam and adaptor piece as described in the patent application referred to, necessitating the provision of three formed pieces. According to this invention, the latch may be operated by a cam member (shown in Figure 7) formed from a single stamped blank, providing spaced cam parts 104a, 104b, connected by a web portion. Locating discs 104d, 104e fitting in recessed seats in the latch housing through which the spindle passes are connected to and spaced from cam parts 104a and 104b respectively. Alined square holes are formed in each locating disc and in the web by which the cam member may be mounted on the spindle to operate a latch of the form shown in Fig. 6.

It will be evident that I have provided improved locking and operating means for door latches of the kind described and have described and illustrated preferred embodiments of the invention, but it is to be understood that various changes and modifications may be made by those skilled in the art, without departing from the scope of the claims appended.

I claim:

1. Latch mechanism for a door including: an outside handle; latching means for said door; a spindle on which said outside door knob is secured and rotatable to retract said latch and extending on the opposite side of the door; an inside door knob secured to said spindle; locking means operable from inside the door to prevent rotation of said spindle; resilient means normally operative to hold said spindle in position to be held by said locking means when operated but enabling said spindle to be moved axially by an axial pull on said outer handle to be released from said locking means while remaining in engagement with said latching means to enable the door to be opened from the outside notwithstanding that the locking means remain in locking position.

2. Latch mechanism as set forth in claim 1, and in which said spindle comprises an outer portion to which the outer handle is secured and which operates to withdraw the latch mechanism to open the door; an inner portion to which the inner handle is secured; clutch means adapted to connect the inner and outer spindle sections; and resilient means normally holding said clutch in position to ensure unitary rotatory movement of the inner and outer portions of the spindle.
